LUBRICATING APPARATUS

Frank S. Barks, St. Louis, Mo.

Application May 19, 1930. Serial No. 453,664

1 Claim. (Cl. 221—47.3)

This invention relates to pumping apparatus, and with regard to certain more specific features, to automatic and portable apparatus for pumping heavy, viscous or semi-viscous material such as grease, putty and the like.

Among the several objects of the invention may be noted the provisions of a portable grease gun having an air motor as part of the gun, said motor having a manual control and acting continuously when put into operation, as distinguished from intermittent motor action requiring a separate manual operation for each ejection of grease; the provision of a grease gun of the class described wherein repeated ejection of grease is effected at high pressures; the provision of a device of the class described which may be readily filled and which operates positively and dependably; and the provision of apparatus of the class described which has said 20 features in a compact and rugged form of light weight. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claim.

In the accompanying drawing, in which is illustrated one of various possible embodiments of the invention,

Fig. 1 is a longitudinal section of the apparatus, certain parts being shown in elevation;

Fig. 2 is a left end view of the apparatus, certain parts being broken away; and,

Fig. 3 is an enlarged section showing details of a valve.

Similar reference characters indicate corresponding parts throughout the several views of the drawing.

Referring now more particularly to Fig. 1, there is illustrated at numeral 1 a body which is suitably cored to provide the passages and/or chambers to be described hereinafter. This body 45 1 is provided with a cap 3, the latter having a longitudinal extension 5 forming an air passage and grip for the hand of an operator. Attached to the base of the cylinder 1 is a grease supply chamber or cylinder 7 which extends substantially parallel to and longitudinally below the grip 5. An outlet line 9, preferably of the flexible type, is fastened to said body 1, this outlet having a suitable coupling member 11, for fastening the same to fittings and the like, on apparatus which is to be greased. A preferably

flexible air line 13 supplies air to the hollow interior of the grip 5.

In detail, the grip 5 includes an air strainer 15 at the inlet and an outlet port 17, said port 17 communicating with a spring seated, line valve 19. The seating action of spring 21 is aided by the pressure of the air in the grip 5. The valve 19 includes a stem 23 having a suitable sealing gasket 25 and an outward extension 27. The outward extension 27 is engageable by a trigger 29 which is operable by the finger of an operator whose hand encircles the grip 5. The trigger is pivoted at pin 31 on the cap 3.

Passage of air through the port 17 is controlled by the valve 19, which in turn is controlled by the trigger 29. When the valve 19 is open, air passes from said port 17 to a passage 33 leading to an automatic, full-stroke valve in the cap 3. This valve will be explained in detail hereinafter.

By means of said automatic, full-stroke valve, in the cap 3, air is intermittently forced behind a piston 35 which rides in a cylinder 37 formed interiorly of the body 1. This air is also intermittently exhausted by means of this valve from behind said piston 35, the piston being returned to an initial position by means of a compression spring 39 positioned behind it in the cylinder 37, this spring 39 reacting against a pump bushing 43 in one end of said cylinder 37.

The piston 35 is provided with a plunger 41 which is reciprocable in the pump bushing 43, the said bushing 43 having an inlet passage 45 in communication with said supply chamber or cylinder 7, a suitable strainer or screen 47 being held across said passage by an anchored washer 2. A spring-pressed outlet check valve 49 is used as an outlet from the bore 51 of the pump bushing 43. On the down-stream side of the check valve 49 is an outlet passage 53 communicating with said flexible line 9.

There is also on the down-stream side of this check valve 49 a release valve 55 which serves the purpose, by opening, of relieving or releasing air pockets, should the device lose its prime because of such pockets. This valve 55 can be opened manually and closed in the same manner.

Referring now more particularly to the cylinder 7, it will be seen that it is threaded at its base 57 for manually screwing it to and unscrewing it from the correspondingly threaded body 1. This cylinder 7 is provided with a lower piston 59 which rides slidably in the cylinder 7 and also slides on a locking rod 61. A

spring 63 normally reacts from the outer head 65 of the cylinder 7 against the follower 59, tending to press said follower toward the body 1 and to force grease in the cylinder 7 to the 5 inlet 45 of the pump. Atmospheric pressure on the follower 59 aids this action, on the suction stroke of said pump.

A laterally movable latch 67 is positioned in the head 65 of the cylinder 7, normally pressed 10 by a spring 69 against the rod 61. The rod 61 is provided with a groove 71 adapted to be co-operated with by the latch 67 when the rod 61 is withdrawn from the cylinder 7. Withdrawal may be made by grasping and pulling out a 15 handle 73. A head in the form of a nut 75 is used on the opposite end of the rod 61 for abutting the follower 59 when the rod 61 is withdrawn, so that the follower may, when it is placed near the head 65 of the cylinder 7, be 20 there held by co-operation of the latch 67 with the recess of notch or groove 71.

Referring now to the automatic valve in the cap 3, it will be seen to comprise a control stem 76 having a loose or self-aligning attachment 25 with the piston 35, said attachment comprising a cross pin 77 in the stem located within a recess 79 in the piston, the stem 76 passing loosely through an opening communicating with said recess 79. By this means, the stem 76 and piston 35 need not be absolutely concentric when assembled and still the piston can operate the stem.

The stem 76 passes through a packing gland 81, said gland 81 being affixed to a stationary 35 ported sleeve 83, said sleeve 83 being forced into the cap 3. This sleeve 83 is provided with oppositely disposed inlet ports 85, one of which is in communication with the passage 33 and the other with that part of the cylinder 1 which is 40 above the piston 35. These inlet ports 85 are adapted to be put into communication with one another by a groove 87 of a central slideable sleeve 89, located in the fixed sleeve 83 (Fig. 1). The ports 85 are also adapted to be cut out of 45 communication with one another by said sleeve 89 when the sleeve is in the alternative position shown in Fig. 3 of the drawing. In the position shown in Fig. 1, the sleeve 89, by reason of the alignment of its groove 87 with the ports 85, is 50 permitting air to pass in behind the piston 35 to force the same down, against the reaction of the spring 39. This causes the plunger 41 of the pump to make a pumping stroke, thus forcing 55 grease from the apparatus.

55 The stationary sleeve 83 is also provided with outlet ports 91, the lower one of which communicates with that part of the cylinder 37 which is above the piston 35, and the upper one of which communicates with an exhaust port 93 in the 60 cap 3.

At its upper reaches the movable sleeve 89 is provided with grooves 95 which communicate one with the other by reason of the fact that the sleeve 89 is smaller in diameter at, between, and 65 above said groove than it is below said groove. Below the groove the sleeve 89 exactly fits the sleeve 83 for sliding and sealing contact, whereas above and between said grooves 95, the sleeve is cut down. Thus, when the sleeve 89 is in its 70 downward position (Fig. 3), the ports 91 are in communication by way of the grooves 95 and said cut-down portion.

The grooves 95 are also used in co-operation with a pair of detents shown in Fig. 2. These 75 detents comprise balls 97 pressed by springs 99,

said springs reacting against hollow acorn nuts 101, the nuts 101 being threaded into the cap 3. It will be seen that these detents 97 function to hold the movable sleeve 89 in predetermined upper and lower positions. In the upper position of the sleeve 89, the inlet ports 85 are put into communication by the groove 87 (Fig. 1). In the lower position of the sleeve 89 the exhaust ports 91 are put into communication by the space between the sleeves 83, 89 (Fig. 3).

80 The method of automatically operating the movable sleeve 89 to reciprocate is by means of said stem 76. The stem 76 is provided with spaced attached shoulders 103, that part of the stem 76 between said shoulders 103 passing slidably through a reduced opening in an inward shoulder 105 of the sleeve 89. Loose, slideable springs 107 are positioned over the stem 76 and between the shoulders 103 on said collar and shoulder 105. The upper end of the valve, including the upper end of the stem 76 is positively enclosed by an acorn nut 109.

90 The operation is as follows, starting from the Fig. 1 position:

Air under pressure enters from the line 13 and 100 passes through the grip 5. If the trigger 29 is not pressed, said air is stopped at the valve 19.

When the trigger 29 is pressed, the valve 19 is opened and air passes from the grip 5 through ports 17, passage 33 one of said openings 85, 105 groove 87, the other of said openings 85 and behind the piston 35, driving said piston 35 down in its cylinder to cause the plunger 41 to effect a stroke and eject a charge of grease out through the check valve 49 and through line 9 to the 11 fitting in connection with the coupling 11.

As the piston 35 is driven down, it draws the stem 76 because of the co-operation at pin 77. After some movement this causes the upper shoulder 103 on the stem 76 to engage the upper 115 spring 107 and compress the same. The spring 107 has such a tension that it will compress to same degree before moving the movable sleeve 89. In fact, the piston 35 can almost reach the end of its stroke (take a full stroke) before the 120 upper spring 107 is compressed enough to effect a motion of such sleeve 89. However, when the sleeve 89 does move, it moves quickly and completely. When movement takes place, it, like the piston movement, is a full stroke movement, 125 wherein the detent 97 becomes positioned in the upper one of said pair of grooves 95.

As the movable sleeve 89 changes its position, the inlet ports 85 are put out of communication (see Fig. 3) and the exhaust ports 91 are put 130 into communication by the grooves 95 and the reduced portion between them. Immediately, the reaction of the spring 39 takes effect to raise the piston 35 and plunger 41, thereby causing another charge of grease to enter the plunger 135 cylinder 51 from the cylinder 7. This also results in the stem 79 being lifted as air is exhausted from the piston 35. After some movement, the lower spring 107, taken into connection with the detents 97, has the same delayed 140 action as has the upper spring 107, so that the volume of air above the piston 35 can be emptied before the valve resets to its inlet position shown in Fig. 1.

145 From the above it will be seen that the reciprocal action of the piston 35 and valve is continuous, as long as the trigger 29 is held by the operator, provided, that the outlet pressure does not rise sufficiently high to equalize the pressure of the air against piston 35. This appa- 150

5 ratus comprises an improvement in the art, because there is provided a portable grease gun having an air motor which will continue operation as long as the trigger is held in open position. This is an advantage over those pieces of apparatus wherein the trigger must be pressed each time that a stroke of the pump is effected. This feature effects a great saving in time and energy.

10 10 The advantageous arrangement of the grip 5, parallel to the supply cylinder 7, taken in connection with the lateral arrangement of the pump plunger and valve, results in an exceedingly compact device of light weight. The location 15 interiorly of the stem 76 also conserves space and provides a fully enclosed structure of neat appearance and trouble-proof characteristics. The whole device may be held in one hand and the trigger manipulated therewith while the other hand effects connections by means of the coupling 11.

15 20 In order that the valve in the head 3 may be oiled, I provide a chamber 108 filled with a felt wick, or the like 110, enclosed by a cap 111. A chamber 113 is formed below the felt or the like 110 and in this chamber is located a loosely fitting disc or slug 115. This disc 115 normally seals off an opening 117 in communication with the passage 33. However, when the trigger 29 is 25 30 pressed and air is permitted to flow into the passage 33, said air presses the disc against the felt or the like 109. The felt is oil soaked and the pressure of the disc 115 against the same results in squeezing out some oil which flows down the narrow passage 117 and into the passage 33, whence it is carried into the valve and valve chamber and lubricates the same. Whenever the valve cuts off the flow of air, the disc 115 drops down again and closes the passage. Thus 35 40 at each stroke of the valve, the action of the air itself causes a slight amount of oil to be exuded into the air, to lubricate the parts. Some of this oil also finds its way down into the main cylinder in which the piston 35 operates. It will be noted in this connection that the stem 76, as well as the other parts of the valve are fully enclosed by the nut 109 and thus the oil is not lost on each stroke and very little is required. This feature also results in no air being substantially lost by leakage before it gets behind the piston 35.

45 50 From the above, it will be seen that as the grease is received from the cylinder 7 and compressed by the pump that the follower 59 in the cylinder 7 forces the grease. After all of the grease has been used from the chamber or cylinder 7 (about a pound) the cylinder 7 is easily refilled. This is done by unscrewing the cylinder 7 from the body 1 and pressing the same downwardly into a mass of grease. This causes the follower 59 to compress the spring 63 and travel to the head end 65 of the cylinder 7.

55 60 After the cylinder 7 has been completely filled, the stem 61 is retracted by pulling on the handle 73. When the latch 67 is reached by the recess 71, the latch drops into said recess and holds the stem 61. At this time the head 75 is against the follower 59. Thus the cylinder, which is now full of grease, may be removed from the supply of grease and screwed into the body 1. Thereafter, the latch 67 is released and the rod 61 is pressed into the cylinder 7. The rod 61 is thus 65 70 out of the way. As soon as the rod 61 is put into the inward position described, the follower 59 becomes active against the grease and pushes the same out of the cylinder 7 under the action of the expansion of spring 63. The apparatus is 75 80 then ready for use to deliver grease upon pressure of the trigger 59.

85 90 Attention is called to the relationship between the area of the piston 35 and the area of the plunger 41. These are arranged so that a multiplication of pressure is effected on the grease being pumped as compared to the pressure of the air used. For instance, the area ratio may be of the order of 20 to 1 so that with 100 pounds per square inch of air pressure, about 2000 95 100 pounds per square inch pressure may be effected upon the grease, making due allowance for the efficiency of the mechanism.

100 105 In view of the above, it will be seen that the several objects of the invention are achieved and other advantageous results attained.

110 As many changes could be made in carrying out the above constructions without departing from the scope of the invention, it is intended that all matter contained in the above description or shown in the accompanying drawing shall be interpreted as illustrative and not in a limiting sense.

I claim:

115 In apparatus of the class described a flexible air line, a portable grease gun attached to said line and receiving air therefrom, said gun being adapted to be supported in one hand, a lubricant supply chamber associated with the gun, an outlet line, a reciprocating pump adapted to withdraw lubricant from said supply chamber and deliver the same to said outlet line, a starting valve having a passage leading from the air supply to the pump, a valve gear located in the passage between the starting valve and the pump, 120 the actions of the valve gear and pump being coordinated so as to effect continuous reciprocation of the pump when said starting valve is held open, the center line of the supply chamber and of the pump being arranged at a substantial right angle, said valve gear comprising a valve 125 stem arranged substantially concentric with the center line of the pump, a sleeve surrounding said stem, said sleeve being supported to control air fluid to the pump, and a lost motion engaging means between said stem and said sleeve. 130 135

FRANK S. BARKS.
